UNITED STATES PATENT OFFICE.

CHARLES H. LEONARD, OF GRAND RAPIDS, MICHIGAN.

DESIGN FOR A LATCH CASE AND HANDLE.

SPECIFICATION forming part of **Design No. 21,118**, dated October 20, 1891.

Application filed August 14, 1891. Serial No. 402,689. Term of patent 7 years.

To all whom it may concern:

Be it known that I, CHARLES H. LEONARD, a citizen of the United States, residing at Grand Rapids, in the county of Kent and State of Michigan, have invented and produced a new and original Design for Door-Latch Handles, of which the following is a specification, reference being had to the accompanying drawings, forming part thereof.

10 Figure 1 is a front view of the casing of a door-latch with my handle pendent, and shows my design in front elevation; and Fig. 2 is a side elevation of the same, these two views being deemed necessary to fully illustrate my

15 design.

The casing is ornamented by scroll-work in relief, as shown.

My design is for a latch-case rectangular in outline, having a **U**-shaped handle provided with an ornamentation resembling the 20 bottom of a horseshoe with toe and heel calks and creasings with nail-heads in relief, and is pendent from the front of the face of the casing, as shown.

What I claim is—

25 The design for a latch case and handle, substantially as herein shown and described.

In testimony whereof I affix my signature in presence of two witnesses.

CHARLES H. LEONARD.

Witnesses:

DENNIS L. ROGERS,
MAY MOULTON.
